United States Patent Office

Des. 186,438

Patented Oct. 27, 1959

186,438

TELEVISION REMOTE CONTROL OR SIMILAR ARTICLE

Clement W. Alley, Lombard, Ill.

Application June 9, 1959, Serial No. 56,362

Term of patent 7 years

(Cl. D26—13)

Fig. 1

Fig. 2

Fig. 1 is a perspective view of a television remote control or similar article, showing my new design, the opposite side being substantially a mirror image thereof; and

Fig. 2 is an elevational view of the end thereof farthest from a viewer of Fig. 1.

I claim:

The ornamental design for a television remote control or similar article, as shown and described.
